Attorney

UNITED STATES PATENT OFFICE.

FRANCIS M. CROSSLEY, OF DAYTON, OHIO.

COMBINATION RAIL AND TIE FASTENER.

No. 808,904.

Specification of Letters Patent.

Patented Jan. 2, 1906.

Application filed September 21, 1905. Serial No. 279,393.

To all whom it may concern:

Be it known that I, FRANCIS M. CROSSLEY, a citizen of the United States, residing at Dayton, in the county of Montgomery and State of Ohio, have invented certain new and useful Improvements in Combination Rail and Tie Fasteners; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to new and useful improvements in fastening devices for metallic cross-ties and by means of which the steel rails are rigidly connected to said ties without employing screw-openings or bolt-openings or 20 any kind of openings in the ties or rails.

The invention is not only suitable owing to its simplicity and convenience as a permanent means for connecting rails with metallic ties within a bed of concrete, but it is highly practicable and available in temporary construction-work where it is desired to quickly lay a temporary track. The fastening means is further highly serviceable as a single device may be utilized in connection with any of the 30 forms of metallic ties employed in railway construction.

Preceding a detail description of the invention, reference is made to the accompanying drawings, of which—

35 Figure 1 is a cross-sectional view illustrating my improved rail-fastener in position within a bed of concrete. Fig. 2 is a detail view of the fastener, looking to the right in Fig. 1; Fig. 3, detail views showing the cross-sectional forms of a variety of metallic ties any one of which is available for the uses and purposes of my improved fastener.

In a detail description of the invention similar reference characters indicate corresponding parts.

45 The structural features of my improved rail-fastener are embodied in the form of a clamp 1, which has an angular opening consisting of parts 2 and 3, which communicate in the form of a T. From the upper portion of the clamp there extends laterally a lip or projection 4, which clamps the edge of the rail-flange 5 and clamps said rail firmly against the top of the cross-ties 6. Through the top of the clamp 55 there is a screw-threaded opening 7, which is substantially in alignment with the body of

the clamp. This opening receives a binding-screw 8, which engages the top of the cross-tie in the middle thereof and rigidly unites the cross-tie and the rail. This screw has a 60 suitable wrench-head, by means of which a proper leverage may be applied to the screw. The opening in the clamp at the bottom is of a tapering form to provide a bearing-surface on one side of the clamp, which, in effect, forms 65 a fulcrum for the points of contact 10 and 11, which, it will be observed, are the engaging points between the screw and the cross-tie and between the clamp and the rail-flange. Owing to the formation of the opening in the 70 clamp, it is adapted for use in connection with any of the forms of cross-ties as shown in Fig. 3. In the use of either of these forms of cross-ties the binding-screw 8 is the same in its operation and the points of contact between the clamp and the rail, and between the binding-screw and the tie, and the clamp and the tie are the same.

The simplicity and utility of this fastener can but be readily appreciated. In its operations it is simply slipped over the ends of the ties and is loosened sufficiently to engage the rail-flange, after which the binding-screw is properly tightened and a most rigid and lasting connection between the rails and the ties 85 is obtained.

Owing to the fact of there being no necessity for bolt or screw openings in the rail-flange or the ties, these clamps may be utilized in the tearing up of old tracks and the 90 relaying of new ones.

Having described my invention, I claim—

1. In a rail - fastener for uniting rails to cross-ties, a clamp having a suitable opening for the tie, a lip projecting from said clamp 95 and embracing the upper surface of the rail-flange, and a screw penetrating the top of said clamp and engaging the upper side of the rail, and effecting three points of contact when the device is rigidly secured in position. 100

2. A clamp for fastening rails to metallic ties consisting of a member having an opening therein to receive the tie, the lower surface of said opening being of tapering form, a lip projecting from one side of said member and engaging the rail-flange, and a screw penetrating the upper end of said clamp and engaging the tie. 105

3. In a fastener for rails, a clamp having a suitable opening to receive the tie, a screw 110 passing through the upper portion of said clamp in alignment with the center of the tie-

- opening, a lip extending on one side of said screw and adapted to project over the rail-flange, the lower surface of the tie-opening in said clamp being of tapering form to provide
5 a bearing-point between the lower side of the tie and the bottom of the clamp which engages said tie at a point between the contact-point of the screw and the tie, and the contact-point of the clamp and the rail-flange.
- 10 4. A clamp for securing rails to metallic cross-ties, the same having a T-shaped opening to receive the rail, the lower surface of said opening being of tapering form to engage the bottom of the rail at one side of the clamp,

a lip projecting laterally from the upper side 15 of the clamp to engage the rail-flange above the point of contact between the bottom of the tie and the bottom of the clamp, and a screw passing through said clamp and engaging the upper surface of the tie at a point opposite the 20 engagement between the clamp and the rail-flange.

In testimony whereof I affix my signature in presence of two witnesses.

FRANCIS M. CROSSLEY.
